[57] CLAIM

The ornamental design for an anti-theft anchor, as
shown and described.

DESCRIPTION

FIG. 1 is a top perspective view of anti-theft anchor
showing my new design,

FIG. 2 is a top plan view thereof on an enlarged scale;
FIG. 3 is a bottom plan view thereof on an enlarged
scale;

FIG. 4 is a front elevational view thereof on an enlarged
scale;

FIG. 5 is a rear elevational view thereof on an enlarged
scale;

FIG. 6 is a right side elevational view thereof on an
enlarged scale;

FIG. 7 is a top perspective view of a second embodi-
ment of my new design;

FIG. 8 is a top plan view thereof on an enlarged scale;
FIG. 9 is a bottom plan view thereof on an enlarged
scale;

FIG. 10 is a right side elevational view thereof on an
enlarged scale the left side being a mirror image; and

FIG. 11 is a rear elevational view thereof on an en-
larged scale, the front being a mirror image of that
shown in FIG. 4 of the first embodiment;

FIG. 1
